WINDOW BRACKET

George B. Grafton, Irwin, Pa.

Application October 20, 1931. Serial No. 570,022

4 Claims. (Cl. 304—24)

This invention relates to window brackets for the use of painters, window washers, and the like. An object of the invention is the provision of a window bracket adapted to be adjustably positioned in holding engagement with a window frame and sill assembly, and having guard means associated therewith which is collapsible upon the main body of the bracket to facilitate transportation. Another object of the invention is the provision in a bracket of this character of novel means for adjusting and holding the bracket in adjusted position. Other objects include the provision of a window bracket which is rugged, durable, and which fulfills all known safety requirements dealing with devices of this general nature.

In the drawings:

Figure 1 is a perspective of a window bracket as constructed in accordance with this invention.

Figure 2 is a side elevation thereof as in guard collapsed position.

Figure 3 is a top plan view of the bracket as mounted in service.

Figure 4 is a section on the line 4—4 of Figure 3.

Figure 5 is a section on the line 5—5 of Figure 3.

Figure 6 is a section through the retaining bar assembly.

Broadly the invention consists of a platform slidably adjustable over supporting bars or arms arranged thereunder and which have associated therewith means for anchoring the arms with respect to a window frame so that the platform extends outwardly thereof over the window ledge. The platform carries a guard rail assembly which is collapsible thereon for transportation and the platform is further provided with suitable window ledge engaging rests having means thereon for securing the platform in adjusted position with respect to its supporting bars.

In detail the structure comprises a platform having a deck made up of flooring strips 10 occupying its central portion between side edge flooring strips 11 which are of greater width than the strips 10, all of the strips 10 and 11 being appropriately secured to cross sills 12, 13 and 14 extending therebeneath adjacent the rear edge, the central portion, and the front edge respectively of the platform.

Each of the side edge deck strips 11 at its junction with the central cross sill 13 has associated therewith a depending substantially U-shaped metal guide 15, the upstanding side arms of which are bent to form perpendicular shoulders 16 adapted to seat against a metal bearing

plate 17 resting against the under face of the sill 13 to avoid injury to the sill by reason of wear. The perpendicular shoulders 16 extend laterally on opposite sides of the guide and terminate in upstanding parallel arms 17', the outer of which bears against the outer side of the associated strip 11 and cross sill 13 and the inner of which extends upwardly through an aperture 18 provided for the purpose in the cross sill and through a seating notch 19 in the adjacent side of the deck strip 11. On top of each of the deck strips 11 a bearing plate 20 is provided having upstanding parallel ears 21 at its opposite ends, which ears cooperate with the terminal portions of the arms 17' to form bearings for pivot studs 22 passed therethrough and forming pintles by which the lower end of a guide frame upright side bar 23 and an inclined guide frame brace bar 24 are connected to the platform. Securing elements 25 passed through the shoulders 16, plate 17, sill 13, deck piece 11, and plate 20 serve to secure the parts in assembled service position.

Adjacent the rear edge of the platform the cross sill 12 has at each side edge of the platform a guide 26 associated therewith and of a construction similar to the previously detailed guide 15. The guide 26 is provided with an upstanding side terminal portion 27 cooperating with an ear 28 on a securing plate 29 to receive the pivot stud 30 by which a rear upright guide frame bar 31 is pivotally connected to the rear edge of the platform. The plate 29 and the guide 26 are secured together by fastening elements, one of which is shown as at 32 passed through the respective parts.

At the forward edge of the platform each of the side deck strips 11 has secured thereto a retaining plate 33 having an upstanding ear 34 cooperating with the upstanding terminal portion 35 of a guide arm 36 to receive the pivot stud 37 by which the lower forward end of a guide frame arm 38 is pivotally connected to the platform. Beneath the sill 14 the arm 35 is bent inwardly to provide a perpendicular shoulder 39 having a bearing engagement against a plate 40 on the under side of the sill. At its inner end the shoulder 39 is continued as a part of the guide arm 36 which is formed with an outwardly flared lower end portion 41 having an inwardly directed foot 42 which is rounded on its under face for seating engagement on a window ledge. Cooperating with the member 36 is a similar guide arm 43 arranged in parallel spaced relation with respect thereto and having 110

an oppositely flared lower end portion 44 provided with an inwardly directed foot 45 corresponding to the foot 42. At its upper end the guide 43 is provided with a laterally directed shoulder 46 which seats against the bearing plate 40 and which is anchored thereto by a securing element 47 passed through the shoulder, plate, sill, side strip, and upper retaining plate 33. A similar securing element 47 connects the plate 33 with the shoulder 39 of the guide member 36.

A pivot bolt 48 extends through and between the parallel portions 36 and 43 of the forward guides and provides a fulcrum for a clamping lever 49 pivotally mounted thereon between the arms 36 and 43. The lever 49 has a cam head 50 and the respective guide arms may be clamped tightly against the sides of the cam head 50 by proper adjustment of a nut 51 threaded over the bolt stem 48.

The platform is slidably mounted over spaced supporting arms 52 of channel metal having their respective channel flanges inwardly and oppositely directed. These channel arms 52 are slidably received through the guides 26, 15 and 36-43, and are provided at their forward ends with eyes 53 adapted to receive therethrough a retaining bar 54 comprising a tube having an inner bar 55 slidably disposed within the tube and adapted to bear at its ends 56 against the inside of a window frame 57 when in service position, as shown in Figure 3. The tube 54 and retaining bar 55 are respectively anchored by means of a set screw 58 threaded through a floating ring 59 disposed over the tube 54, which set screw is adapted to extend through an aperture 60 provided for the purpose in the tube 54 and bear against the surface of the bar 55. As best shown in Figure 6, the respective diameters of bar 55, tube 54, and ring 59 are such that there is a limited play between the parts radially thereof. This materially assists the holding action of the set screw 58 when the parts are clamped together.

The platform carries a collapsible guard rail or cage assembly consisting, in an extended position, of upright rear bars 21 connected at their ends by an integral cross piece 61 to which is attached an under brace 62 bearing against the uprights 31. A side bar 63 extends across the rear of the platform between the uprights 31 and is formed with forwardly directed arms 64 which are pivotally attached to the uprights 31 and at their ends to the side bars 23. Above the side bar 33 is disposed a similar side bar 65 having forwardly extended side arms 66 pivotally attached to the uprights 31 and the upper ends of the side bars 23. The side bar 65 is further provided with an inner brace element 67 cooperating with the arms 66. Each of the upright side bars 23 is braced against side strain by connection with the diagonal brace bar 24 and further protection at the sides of the cage is provided by means of pivoted links 68 connected between the upper ends of the uprights 31 and the upper ends of the side bars 23.

At the upper end of each of the side bars 23 there is pivotally connected the end of a brace bar 69 adapted to extend forwardly and downwardly with respect to the platform and which has its lower end pivotally attached to the upper end of the associated bar 38 by means of a pivot stud 70. A slip sleeve 71 is adapted to slide over the brace arm 69 and to seat on the head of the stud 70 to cover the break-

joint and maintain the brace bar in service position, as shown in Figure 1.

Prior to use the bracket is collapsed into the position of parts as shown in Figure 2 so that it may readily be transported and placed in position in a window frame with the retaining bar assembly 54-55-56 extending across the inside of the window frame. With the device thus positioned the feet 42-45 of the forward guide elements are seated on the window ledge 72, the platform being slidable over the supporting channel bars 52 to effect the necessary adjustment of the parts to accommodate for different sized windows. With the parts thus adjusted the clamping levers 49 are manipulated to engage their cam heads 50 against the under channels of the bar 52 forcing the same into clamped engagement against the under side of the platform and thereby securely holding the platform in adjusted position with respect to the supporting channel bars 52. The nuts 51 may then be tightened to clamp the guide sections 36 and 43 against opposite sides of the cams and channel bars providing an additional measure of security and effectively holding the associated parts against any relative slipping movement therebetween. The cage is then extended to upright position by lifting up on the top cross bar 61 and the slip sleeves 71 are engaged over the break-joints 70 to hold the braces 33-69 in extended position against accidental collapse. The device is then in service position with the parts as illustrated in Figures 1 and 3. It is obvious that in order to disassemble the bracket the slip sleeves 71 are raised and the brace arms broken at their joints to permit collapse of the cage upon the platform.

I claim:

1. In a window bracket, a platform, a guard cage carried thereby, guide members on said platform, supporting bars longitudinally slidable in said guides, means for anchoring said bars in a window frame to extend outwardly therefrom, leg members rigidly secured to said platform and adapted to bear against a window ledge, and means for clamping said leg members into holding engagement with said supporting bars.

2. A window bracket comprising a platform, a guard cage carried thereby, guide members consisting of metal strip pieces rigidly attached to said platform and having portions shaped to provide supporting leg members at opposite sides of the platform, said cage having bracing bars connected directly to said guide members, supporting bars longitudinally slidable through said guide members, means for anchoring said bars in a window frame to extend outwardly therefrom, said leg members being adapted to bear against a window ledge, and clamping means for engaging said supporting bars beneath the same, said clamping means being mounted upon and operable between the leg members.

3. In a window bracket, a platform, window ledge engageable leg members carried thereby adjacent one edge and consisting of pairs of substantially parallel metal strips spaced apart, platform supporting bars slidably engageable between the spaced elements of said leg members, means for anchoring said supporting bars in a window frame, and clamping elements pivotally mounted between the elements of said leg members for engaging against the under faces of said supporting bars to bind the same against the bottom of said platform.

4. In a window bracket, a platform, a guard cage carried thereby, supporting bars beneath said platform and extending forwardly thereof, said bars having eyes formed therein at their forward ends, a bar adapted to be disposed transversely through the eyes of the supporting bars for engaging the inside of a window frame, a sleeve disposed through said eyes and receiv-

ing said bar in concentric relation, said sleeve having an aperture therein, and a clamping sleeve slidable over said first named sleeve and having a clamping bolt threaded therethrough for engaging said bar through the aperture in said first named sleeve. 80
